UNITED STATES PATENT OFFICE.

ANSELM T. NYE, OF MARIETTA, OHIO.

GAS OR VAPOR STOVE.

1,209,325.

Specification of Letters Patent. Patented Dec. 19, 1916.

Application filed January 27, 1916. Serial No. 74,646.

To all whom it may concern:

Be it known that I, ANSELM T. NYE, a citizen of the United States, residing at Marietta, in the county of Washington and State of Ohio, have invented certain new and useful Improvements in Gas or Vapor Stoves, of which the following is a specification, reference being had therein to the accompanying drawing.

- 10 This invention relates to certain new and useful improvements on gas or vapor stoves and more particularly to the ovens therefor; the object being to provide a stove with a pair of superposed ovens each being provided with an independently controlled burner whereby the lower or broiling oven can be utilized for a baking or roasting oven when the upper or baking oven is in operation.
- 20 Another object of my invention is to provide a stove with a pair of superposed ovens which can be used independently of each other; the same being so constructed that either oven can be used alone or both of the ovens can be used at the same time.

Another object of the invention is to provide a stove in which each of the ovens is provided with an air inlet for supplying air to the burner and with an outlet communicating with a flue so as to cause the heat units to circulate through the oven.

Another and further object of the invention is to provide an oven in the form of a casing having a broiling pan adjustably mounted within the lower portion of the casing forming a top for the lower oven.

Another and further object of the invention is to provide a stove which is exceedingly simple and cheap in construction, the grid over the lower burner being provided with a seat for a rectangular baffle plate and a seat for a circular baffle plate, either one of which can be used in connection therewith so as to distribute the heat units in the lower oven.

Other and further objects and advantages of the invention will be hereinafter set forth and the novel features thereof defined by the appended claims.

50 In the drawings—Figure 1, is a side elevation of a stove showing the application of my improved construction of ovens thereto; Fig. 2, is a detail vertical enlarged section through the lower oven and a portion

of the upper oven; Fig. 3, is a horizontal section through the lower oven; and Fig. 4, is a vertical section through the superposed ovens.

Like numerals of reference refer to like parts in the several figures of the drawings.

In the drawings, 1 indicates a support which I have shown in the form of a stove top having a suitable opening to receive a grid 2 which is provided with a rectangular seat 3 adapted to receive a rectangular baffle plate 4; said grid having a circular opening in which can be arranged, a circular baffle plate 5, these baffles being interchangeable in their respective seats so as to allow either of the baffles to be used in order to distribute the heat units, as will be later described. Mounted on the support 1 is a casing 6 provided with an enlarged portion 7 the opposite walls of said casing being provided with stepped portions 8 and 9; 75 the stepped portions 9 forming supports for shelves 10. A bottom plate A is arranged within the casing at the junction of the enlarged portion and is provided with cut-away portions at its edges to allow the heat units arising from the burners to pass into the baking oven.

Arranged on the supports formed by the stepped portions 8 is a broiling pan 11 forming a top for the broiling oven formed by the casing 6. It will be seen that this broiling pan can be inverted and moved into various positions in respect to the burners as will be hereinafter described.

The baking oven is provided with a suitable door 12 and the broiling oven with a door 13 having a series of air inlet openings 14 and 15 out of alignment for supplying air to the upper burners.

When used as shown and described, an extension 16 is formed on the supply pipe 17 of the stove top and is provided with a burner 18 arranged under the grid 2 and with one or more inverted burners 19 arranged above the broiling pan 11 under the plate A. Air is supplied to the burner 18 through the open-work of the stove top and the heat units escape from the broiling oven through outlets 20 formed in the back of the oven which communicate with a vertical flue formed to the rear of the casing 6; said flue having a vertical partition forming spaced flues 21 and 22 which are contracted

at their upper ends and terminate in a thimble 23 to which an ordinary stove or smoke pipe can be connected for conveying the smoke and heat units out through the chimney in the ordinary manner.

The upper oven is provided with a series of outlet openings 24 communicating with the flue 21 so that the heat units after circulating through the oven pass into the flue and out of the stove pipe. Air is supplied to the upper burners 19 through the air inlet openings 14 and 15 formed in the door of the broiling oven and it will be seen by this construction that each burner is provided with a separate circulation for the heat units so that each oven can be used independently of the other.

When both the upper and lower burners are in use, the broiling oven can be used to good advantage for baking and roasting purposes as the heat units from the upper burners 19 will be deflected from the bottom A against the broiling pan so as to form heating means for the top of the oven and as the heat units strike the baffles carried by the grid from the lower burner, I am able to heat the lower oven in such a manner that anything placed therein will be roasted quickly and by inverting the broiling pan, the same can be used for broiling purposes.

From the foregoing description, it will be seen that I have provided a stove with a pair of superposed ovens formed by a casing having a division plate separating the ovens; each oven being provided with an independently controlled burner having means for conveying air to each burner and means for carrying off the heat units into separate flues. By this construction, either of the ovens can be used independently or both together.

I claim:

1. A gas or vapor stove having a pair of superposed ovens separated by a plate, a burner arranged under the upper oven, a broiling pan arranged within said lower oven under said upper burner forming a top for the lower oven chamber, a burner arranged under the lower oven chamber each of said oven chambers being provided with an independent outlet opening communicating with a flue.

2. A gas or vapor stove having a pair of superposed ovens each provided with an independently controlled burner, a broiling pan arranged in one of said ovens forming a top therefor, a plate arranged over the upper burner, each of said ovens being provided with an air inlet adjacent the bottom

thereof and each of said ovens having an independent outlet communicating with flues formed to the rear of said oven.

3. A gas or vapor stove having a casing provided with a division plate forming a pair of superposed communicating oven chambers, each oven chamber having a door, the lower door being provided with air inlets, a burner arranged under said plate supplied with air by said air inlets, a broiling pan arranged under said burner and spaced therefrom forming a top for the lower oven chamber, a burner arranged under the lower oven chamber, each of said oven chambers being provided with an independent outlet communicating with a flue.

4. A stove, comprising a support, a grid arranged within said support, detachable baffles for said grid, a casing arranged on said support over said grid having stepped walls, a pan supported by said stepped walls, a plate dividing said casing into chambers, a burner arranged under said grid, and a burner arranged under said plate.

5. A stove, having superposed ovens formed from a casing provided with a division plate, a flue arranged to the rear of said ovens having a central partition forming parallel flues, said flues communicating respectively with said ovens, a door for each of said ovens, one of said doors being provided with air inlets.

6. In a stove, the combination with a pair of superposed ovens each having a burner, a divided flue arranged to the rear of said ovens forming parallel flues communicating respectively with said ovens, doors for said ovens, one of said doors being provided with a series of air inlets for supplying air to the upper burner.

7. A stove, comprising a support, a grid arranged on said support, a casing mounted on said support over said grid, interchangeable baffles carried by said grid, a plate arranged within said casing forming superposed chambers, each of said chambers being provided with an outlet, a door for each of said chambers, the door for the lower chamber being provided with air inlets, a broiling pan arranged within the lower chamber, a burner arranged under said grid, and an inverted burner arranged between said broiling pan and plate.

In testimony whereof I hereunto affix my signature in the presence of two witnesses:

ANSELM T. NYE.
